2,632,534

METALLIC MATING AND FRAMING MEMBER

Emanuel Gray, Far Rockaway, N. Y.

Application June 5, 1948, Serial No. 31,334

2 Claims. (Cl. 189—35)

1

My invention relates particularly to anchorage or tie constructions for frames which frequently need to be assembled in panels with one frame arranged side by side or top to bottom with respect to another frame or in a wall construction.

One object is to provide simple, convenient and effective means for mounting or connecting such frames.

Another object is to provide means by which frames may be effectively mounted or connected without the use of bolts, rivets, welds or screws.

Another object is to provide a connection which is water and air tight.

Another object is to provide a simple, compact and light connecting device which can be readily made according to a predetermined standard for use with commercially made frames.

Another object is to provide a construction especially adapted for uniting adjacent metal frames such as are used for windows, doors and the like.

A special object is to provide a mating bar for connecting two metallic frames.

Another object is to provide a bar which will conform itself to the corresponding edge of the members to be joined.

Another object is to provide a bar whose web will be in tension when in place securing the edges of the members to be joined.

Another object is to provide a self-aligning bar for connecting two frames or one frame to a support.

Another object is to provide a form of mating bar which may also be used as a framing member.

Another object is to provide a bar which can be used as a mating, framing or glazing member.

Another object is to provide a construction which permits of good architectural design with wide latitude to the designer.

With these objects in view, I provide the marginal edges of the frames with grooves and ribs and provide a tie bar of special cross-section which has ribs and grooves corresponding to the grooves and ribs of the frame and is with difficulty distortable so as to adapt it to the irregularities of the frames and enable a frame to be connected to another frame or to an enclosing frame.

The accompanying drawing illustrates the preferred form of my invention.

Fig. 1 is a front elevation showing two main window frames connected together, each having a swinging sash and with overhead frames connected to the main frames.

Fig. 2 is an enlarged horizontal cross-sectional

2

view on the plane of the line 2—2 of Fig. 1 showing the details of one form of the invention involving two connected frames.

Fig. 3 is an enlarged vertical sectional view on the plane of line 3—3 of Fig. 1, showing the tie bar connecting the frame of a swinging sash to the frame of a fixed sash.

Fig. 4 is a perspective view of a fragment of a tie, mating, framing or connecting bar used for connecting one frame to another or to a support. It may also be used as a framing member.

Fig. 5 is a cross-sectional view showing a modified form of mating bar for connecting two frames having sashes which open in opposite directions.

Fig. 6 is a fragmentary face view showing the corner joint between two mating bars which border a stationary sash and a movable sash on one side and carrier glass on the other side.

Fig. 7 is a sectional view taken on the plane of the line 7—7 of Fig. 6.

Fig. 8 is a face view of the same parts looking at them from the inside, parts being broken away.

Fig. 9 is a sectional view of the parts of Fig. 6 taken on the plane of the line 9—9.

Fig. 10 is a sectional view showing a modified form of construction in which a special tie bar provides means for mounting a window frame in an outer wooden frame.

Fig. 11 is a sectional view showing a similar tie bar for mounting a fixed frame in the opening of a masonry wall.

Fig. 12 shows a sectional view of a window frame mounted in an opening in a wooden frame.

Fig. 13 is a cross-sectional view showing a special joint between two adjacent frame members.

In the form shown in Fig. 1, there are four frames 7, 8, 9 and 10. Frames 7 and 8 are fixed frames and frames 9 and 10 have sashes 11 and 12 which may be hinged to swing in them. These frames and sashes are preferably so designed and constructed that they can be made by a die casting process, each in one piece. These frames in the form shown are made of the same cross-sectional size and shape on all four sides so that they may be joined in many different arrangements by the same size and shape of mating bar.

One marginal corner of each frame (see Fig. 2) is provided with a groove 13 of V-shaped cross-section having an inclined or bevelled approach edge 14. The other marginal corner of the frame has a projecting tongue 15 inclined on its outer face and curved at 16 on its inner face and terminating in a point 17 and having a groove 18. These grooves and inclines are designed to co-

act with elements of the special mating, connecting or tie bar 19.

Bar 19 is formed of metal such for instance as an extruded aluminum alloy and has flanged heads such as an outer head 20 and an inner head 21 connected by a central web 22 at least a part of which is capable of being somewhat distorted so as to adapt the bar to slight irregularities in the shape or location of the frame members which are to be connected and to tightly hold the parts when assembled. The outer head 20 has two flanges with inclined under cut portions 23 to fit the inclined tongues 15 of the adjacent frames and grooves 24 to receive the points 17 of the tongues 15. Each flange 23 has a bulbous end 26 to fit in a groove 18 of the frame. Each rib 27 on head 21 fits a groove 13 in a frame and the edge 28 fits the adjacent inner wall of the frame. The web 22 and head 21 are resilient and in fact capable of bending slightly so that when the ribs and groove are being assembled the flanges of head 21 and the web 22 warp slightly in snapping the ribs 27 into grooves 13.

In Fig. 3 I have shown two frames 8 and 10 assembled by means of a mating or tie bar 19 in exactly the same manner that frames 9 and 10 are connected in Fig. 2. Frame 8 however has a drip flange 31 along its lower edge extending beyond the outer head of the bar 19.

To assemble the two frames of Fig. 2 or Fig. 3, the mating bar 19 is first attached to one frame by hooking the channel end of said bar on to the point 17 of one frame and tilting the bar over until the rib 27 on the opposite head of the bar snaps into the groove 13 on the corner of the frame opposite the projecting tongue 15. The other frame is then attached to the bar by hooking its tongue 15 into the channel end of the bar and then tilting the frame until the opposite edge of the frame engages the flange of the outer head of the bar and the rib 27 receives the groove 13 of the frame.

In the form shown in Fig. 5 two frames such as 10, 10 and sashes such as 12 of Fig. 2 are connected so that one sash can open inwardly and the other outwardly. The two stationary frames 10, 10 in this case are connected by a modified form of mating bar 35 in which the two grooved heads 36 and 37 correspond to the two halves of the head 20 in Fig. 2 and the flanges 38 and 39 correspond to the two halves of the flange 21 of Fig. 2 so as to receive respectively the projections 17 and the grooves 13 of the stationary members.

In the construction shown in Figs. 6, 7, 8 and 9 the horizontal tie bar 19 is connected to the upper edge of the frame member corresponding to that previously described as shown at the right in Figs. 6 and 7 and at the left in Fig. 8. At the left in Fig. 6 and in Fig. 9 the bar 19 serves to support the fixed glass lights 40 and 41 respectively where the ribs 27 serve to space the glass away from the flanges and serve as retainers for the putty bedding 42.

In order to give sufficient clearance to the rib 23 the corners 17 of the frame members are set back slightly at 44 as indicated in Figs. 6 and 8.

In the form shown in Fig. 10 a special form of framing bar 50 is provided in order to position the frame 10 in the opening of a wood frame 51. One end of the bar 50 is provided with a grooved head 52 to receive the flange 17 of a frame. The other edge of the bar is provided with a flange 53 which corresponds with the flange 21 of the bar shown in Fig. 4 for coaction with a groove 13 in the frame member 10. In this case the bar 75

is provided with a flange 54 for attachment to the outer face of the wooden frame and has a return flange 55 serving as a finish and trim to receive the cement 56 or the like. The other edge of the bar 50 is provided with a socket 57 for receiving the edge of the trim 58 which is secured to the inner face of the surrounding frame 51. It will be seen that this bar 50 has many of the features of the mating bar of Fig. 4.

Fig. 11 shows the same form of bar as in Fig. 10. In this case the bar 50 is secured to the masonry wall 60 by a number of anchor plates 61 set into the wall. For this purpose the framing bar 50 is provided with flanges or projections 62 and 63 which fit into slots 64 and 65 of the anchor pieces 61. The glass 66 in this case is mounted directly against the outer face of the flange 53 and secured by putty or the like in a manner similar to that shown in Fig. 9.

The flange 54 serves as a weathering stop between the masonry courses, and the flange 55 forms a pocket 67 to receive suitable caulking or packing.

In the form shown in Fig. 12 the frame member 10 is mounted in a wooden frame 70 and is held in place by the extended flange 17 which projects into a slot 71 in the outer frame. This outer frame 70 is slotted to receive the flange 17 of the window frame and is built about the window frame before the wooden frame is installed. This connection requires no screws or nails whatever to secure the window frame in the outer frame which may constitute or have suitable trim.

Fig. 13 shows a joint formed between two frames 10 and 10' (similar to 7 and 8) in which the frames are oppositely disposed and tongues 15 and 15' are pointed toward each other. In this case the bar 19 may constitute a framing bar. A special section bar 19' has a head 20' somewhat similar to head 20 of Fig. 4 but with a tongue point 17' which fits into the head 20 of bar 19. The opposite edge of bar 19 has a flange 21' like flange 21 of bar 19 and has a flange 21'' offset from the plane of flange 21' so as to overlap flange 21 or bar 19. The parts can thus be easily assembled and held together by rivets, screws or other fastening devices 21X.

It will be noted that the central web of the mating bar is of curved cross-section instead of flat in the ordinary I beam. This makes the mating bar somewhat resiliently compressible and expandable in a plane at right angles to the inner and outer flanges so that the bar is capable of sufficient distortion to facilitate connection of the frames to be joined. When the frames have been joined by the mating bar the central web is under tension which draws the frames tightly together.

It will be seen that the frames and mating bar are provided with cooperating beveled or round edge portions and grooves or recesses which enable the erector to join the parts on the job with a maximum facility. In fact the parts are so joined as to produce in effect a rigid integral whole. Because of the distortionable characteristic of the improved bar it is possible to build or assemble the parts by stages requiring but little pressure. When assembled, it forms a water and air tight joint.

I claim:

1. As an article of manufacture, a mating bar for uniting two members which have grooved edges, said mating bar comprising an elongated central web arched transversely along its length, oppositely extending flanges along one edge of the

central web, each flange having a locking rib along its inner surface for interlocking with the grooved edges of the members to be connected, and a relatively rigid head extending along the opposite edge of the central web, said head having an undercut groove along each of its opposite sides for interlocking with the adjacent edges of the members to be connected, said mating bar being compressible and expandable by reason of the arched formation of the central web.

2. As an article of manufacture, a mating bar for uniting two members which have grooved edges, said mating bar comprising an elongated central web arched transversely along its length, oppositely extending flanges along one edge of the central web, each flange having a locking rib along its inner surface for interlocking with the grooved edges of the members to be connected, said flanges being resilient to permit them to yield along longitudinal axes, and a relatively rigid head extending along the opposite edge of the central web, said head having an undercut

groove along each of its opposite sides for interlocking with the adjacent edges of the members to be connected, said mating bar being compressible and expandable by reason of the arched formation of the central web.
